UNITED STATES PATENT OFFICE.

FRANK UHL, OF SOUTH SHARON, PENNSYLVANIA.

NUT-LOCK.

No. 837,436

Specification of Letters Patent.

Patented Dec. 4, 1906.

Application filed November 14, 1905. Serial No. 287,266.

To all whom it may concern:

Be it known that I, FRANK UHL, a citizen of the United States, and a resident of South Sharon, in the county of Mercer, in the State 5 of Pennsylvania, have invented a new and useful Construction of Nut-Lock, of which the following is a specification.

This invention relates generally to nut-locks, and more particularly to an improved 10 construction of nuts carrying with it means for engaging the thread of the bolt and holding the nut securely locked thereon.

The object of the invention is to provide a 15 simple and efficient means for accomplishing locking operation and one which can be quickly and easily released by one acquainted with its construction.

With these objects in view my invention consists, essentially, in making the nut in two 20 parts, one of said parts being adapted to turn upon the other and carrying a knife adapted to be projected through an opening in the first-mentioned part for the purpose of engaging the thread of the bolt, the movable 25 part carrying a spring-actuated locking-bolt which is adapted to engage a recess in the stationary portion of the nut after the movable portion has been turned a definite amount, thereby securely locking the parts 30 against return movement.

The invention consists also in certain details of construction hereinafter fully described, and pointed out in the claims.

In the drawings forming a part of this specification, Figure 1 is a perspective view of a nut constructed in accordance with my invention, one side thereof being broken away to disclose the knife or blade. Fig. 2 is a top plan view of the lower section of the nut. Fig. 3 is a vertical sectional view taken through the complete nut and showing the same in a locked condition. Fig. 4 is an inverted plan view of the upper section of the nut. Fig. 5 is a sectional view taken through said upper section, and Fig. 6 is a detailed perspective view of the knife.

In constructing a nut-lock in accordance with my invention I employ a lower section A and an upper section B. The lower section 50 A is threaded throughout its entire length, as shown at A'; but the annular upwardly-projecting portion A² has a smooth exterior, and the upper section B is fitted thereon, and the upper end of the annular portion A² is headed down, so as to prevent the upper section B 55 working off. This upper section B, however,

is free to turn upon the annular upwardly-projecting portion of the lower section A.

I have shown my invention applied to a hexagonal-shaped nut; but it will be understood that my invention can be used equally 60 as well upon a four-sided nut or an eight-sided nut, if so desired.

The upper section B is formed with a cam-shaped recess B', which communicates with its central opening, and located in this cam-shaped recess is the cam knife or blade C, having a pivot C', which fits into the depression B², as most clearly shown in Fig. 5. An opening A³ is produced in the upwardly-projected annular portion A², and this opening is of a size to receive the free end of the knife or blade C, and said blade is so shaped that the corner A⁴ of the opening A³ engages or is engaged by the end of the knife or blade 70 when the upper section of the nut is turned and the edge of said knife or blade is projected through the opening A³ and bites into the thread of the bolt. The upper section B is also provided with a socket D, in which is 75 arranged a locking-bolt E, forced downwardly by means of a spring F, which surrounds the upper portion of the bolt E, said bolt being adapted to be projected into a recess G, produced in the upper face of the lower 80 section A when the upper section has been turned sufficiently to bring the locking-bolt 85 over the recess G, and also the locking-bolt is brought into alinement with said recess, the spring acting to force the said bolt into the 90 recess, and by this means the upper and lower sections of the nut are securely locked against any further movement one upon the other. A lateral opening G' is provided, 95 communicating with the recess G, through which a pin may be inserted for the purpose of forcing the bolt E upwardly whenever it is desired to disengage the locking-bolt from the lower section of the nut. The socket D extends entirely through the upper section B, 100 but at its upper end is of less diameter than at its lower end, and this upper end is normally closed by means of a screw-plug D'.

In constructing the nut the upper section carrying the knife and spring-actuated bolt 105 are arranged upon the lower section of the nut, and the upper end of the annular portion A² is headed down in such a manner as to securely connect the two sections together, but still permit the upper section to turn upon the 110 lower section.

In operation the compound nut is screwed

upon the bolt to the desired point, and while the lower section is securely held the upper or outer section is given the necessary turn for the purpose of projecting the edge of the 5 knife or blade into the thread of the bolt and simultaneously locking the upper or lower sections against any further movement.

It will readily be understood that a nut-lock as herein described cannot possibly 10 turn upon the thread, and in order to remove it it is necessary to first release the upper or outer section of the nut, so that the knife or blade can be withdrawn from the thread, and this releasing operation can be accomplished 15 by inserting a pin in the lateral opening G', forcing the locking-bolt E upwardly, and then giving the upper or outer section a forward turn, so as to withdraw the knife or blade.

Having thus fully described my invention, 20 what I claim, and desire to secure by Letters Patent, is—

1. A nut-lock comprising a lower and upper section, the upper section being adapted to turn upon the lower section and carrying 25 a knife adapted to be projected through an opening in the lower section and a spring-actuated locking-bolt carried also by the upper section for engagement with the lower section as specified.

30 2. A nut-lock comprising a lower section having an upwardly-projecting annular por-

tion the interior of said annular portion being threaded, said annular portion having an opening at one side thereof, an upper section having a recess and a socket produced therein, a knife arranged in the recess and adapted to be projected through the opening in the annular portion of the lower section and a spring-actuated bolt arranged in the socket and adapted to engage an opening in the 40 lower section of the nut, as set forth.

3. A nut-lock comprising a lower section having an upwardly-projecting annular portion said annular portion having an opening in one side thereof, said lower section also 45 having a recess, said recess having a lateral opening communicating therewith, the upper section of the nut having a recess and a socket, a knife arranged in the recess and adapted to be projected through the opening 50 in the annular portion of the lower section of the nut and a spring-actuated bolt arranged in the socket and adapted to engage the recess in the lower section of the nut when the upper section is turned upon the lower section to project the knife through the opening 55 in the annular portion in the lower section.
